STEREOSCOPE

John B. N. Cardosa, New York, N. Y., assignor of
one-half to Wilton Bentley, New York, N. Y.

Application June 25, 1934, Serial No. 732,359

5 Claims. (Cl. 88—29)

This invention pertains to improvements for viewing stereoscopic photographs.

Stereoscopic pictures function in pairs. They convey a characteristic impression of depth of view that is a mental composite arising from differences in angle of view in the individual pictures. To this stereoscopic impression it is desirable to introduce an improved balance of relative tone values, and particularly a faithful rendering of color.

An object of this invention, therefore, is to provide means for beholding color in stereoscopic photographs. A further object is to obtain such color impressions or relative tone values by means that are simple, or suitable for inexpensive manufacture in quantities and suitable for use even by children. A further object is to provide color control means that are adaptable to existing stereoscopic viewing apparatus. A particularly important object of this invention is to provide means for altering or adjusting the effect of color at will in viewing stereoscopic pictures, so as to overcome various conditions of physical and physiological nature that contribute to the final composite impression from the stereoscopic pictures. These and other objects will be apparent from the following specific description and accompanying drawing illustrative of this invention.

In the drawing, Fig. 1 represents a stereoscopic viewing apparatus that combines means according to this invention for altering or controlling color impressions of stereoscopic views. Fig. 2 illustrates characteristics or ranges of color of typical color filters for use in a stereoscopic viewing apparatus. Figs. 3 and 4 illustrate modifications of this invention for varying stereoscopic color impressions, while Fig. 5 illustrates another modification of this invention. Figs. 6 and 7 illustrate a further embodiment of the principles of this invention for color control.

This invention is predicated on my discovery that in stereoscopic viewing of images that contain individual differences of tone, composite impressions of color variation may be effected in simple manner by regulating the relative intensity, which also is regulation of effective quality of light for the individual images. For illustration a preferred arrangement is described herein in which black and white images having individual differences of density as color correction are viewed stereoscopically through complementary color filters respectively, with means to vary the relative intensity of light reaching the eyes from the color filters. In brief, this invention

contemplates improvements in controlling or varying the psychological or effective color reception from a pair of stereoscopic images. Preferably the relative intensity or differential illumination of the images is varied.

Referring more particularly to the drawing for purposes of specific illustration of this invention,

Fig. 1 depicts a stereoscopic 1 which houses viewing lenses 2 and 3, and slots or a guideway 4, 5 for holding a pair of stereoscopic pictures before the respective lenses. The form illustrated is adapted to view films by light transmitted through diffusion glasses 6, 7. Each beam of light through the individual pictures traverses a color screen, respectively illustrated as 8 and 9.

Ordinarily these color screens yield color bands that are generally complementary to each other. The pictures being viewed are intended to be printed with corresponding color corrections or local differences of intensity from each other. Thus an object corrected and printed in the one picture of different local intensity or transparency from its print in the companion picture, when viewed solely through a red color filter would appear generally red where red in the original object; while its companion picture when viewed solely through a green color filter would appear generally green where green in the original object. However, when the two pictures are viewed simultaneously through the respective filters in the stereoscope the composite impression should be a blend that contains the two colors in proportion properly to represent the original color appearance of the object. Any number of color objects may thus be viewable in proper tone balance. In ultimate form this presupposes that the density or opacity of the respective color filters be selected or varied to convey more or less of the one color or the other contributing to the general, composite impression of the stereoscope pictures.

With a series of different views, or with different persons observing the views, or with different conditions of light for observing the views, one picture may appear as a pleasing natural color image, but others may appear to contain incongruous color variations from the natural image. Attempts to reproduce natural views in the visual perception of different persons involve at least five independently variable conditions. Thus, differences between the photographs themselves arise from differences in the spectrum of light in which the object is photographed and also from differences of intensity of that light; while further differences arise in the images from

the spectrum of light in which the photographs are viewed and from different intensities of that light. Finally are encountered visual idiosyncrasies of different persons viewing the photographs.

This invention involves means in a stereoscope for correcting impressions of color in the stereoscope beams reaching the eyes of a beholder. Natural objects, art pictures and the like may appear pleasing and natural to different persons and under differing light conditions.

Fig. 2 represents the color ranges of a given pair of filters. More accurately Fig. 2 illustrates that a given filter transmits a band of color or range of wave lengths of light. Thus a certain tone of red, as shown, transmits practically no light of the shorter wave lengths. But from wave lengths of approximately 5500 Angstrom units (A.) to above approximately 7000 A. its transmission is efficient and extensive. A certain tone of green, as shown, transmits effectively the light of wave lengths between about 4500 A. and 6500 A., and also of about 7000 A. Thus a certain balance, or characteristic color tone, is presented by each pair of color filters.

However, the stereoscopic color impression may be corrected in simple manner.

Thus in Fig. 3 is shown a pair of colorless light screens 10, 11, each varying in opacity from one end to the other. These screens may be of glass, or of cellulosic film base, or of other suitable material. The screens are adapted to be inserted between the light sources and the stereoscopic lenses, as for example in slot 8, 9 of Fig. 1. In this latter example the color filters may, if desired, be combined with the ground glasses 6 and 7. The variations in opacity of screens 10, 11 may be opposed and progressive, as shown, or may be as a series of distinct areas of differing intensity. The screens may be separated and moved independently, or a single screen of varying intensity may be used, but as shown an interdependent pair is adapted to be moved simultaneously across the fields. They provide extensive variation in the proportions of light transmitted from the respective filters. Nevertheless the balance of wave lengths from each filter, or the tone of color transmitted by each, remains unchanged. However the adjustment is differential and composite color impression received from both through the stereoscope is thus varied in simple manner.

In the modification shown in Fig. 4, a pair of suitable light screens 12 and 13, of glass, cellulosic film base or other suitable material, not only varies in density over different areas but is suitably colored as well. Thus this screen may be used, if desired, to replace not only density screens 10 and 11 of Fig. 3, but to replace the color filters as well. Such variations may be brought about by increasing layers of colored material or by increasing density of colorant therein. Or, such colored screens as 12 and 13 may be used with given separate color filters and may be selected of such color qualities as to absorb selected wave lengths from certain areas of the predominant color filters. Where screens 12 and 13 are tinted but slightly they have the effect of diminishing the overall color intensity through the respective stereoscope lenses. If desired the screens may be selected to introduce some considerable color change in the light transmitted through the original filters.

Another modification of this invention is shown in Fig. 5. For illustrative purposes Fig. 5 may

be regarded as a section across the stereoscope tubes shown in Fig. 1.

In the modification shown in Fig. 5, diaphragms 14 and 15 of variable openings are interposed in the tubes to diminish the intensity of each of the colored beams from the respective pictures. As shown, each diaphragm is independently adjustable. The effect is to vary the composite color impression in the stereoscopic image.

For further illustration of the principles of this invention, reference is had to Figs. 6 and 7. Fig. 7 is an end view exposed at substantially the line 1—1 of Fig. 6. In this modification variation of the stereoscopic color image is obtained by utilizing individual light sources, from which the light is independently varied. In the form shown, the illustration of a transparent film heretofore used in this specification is continued. The stereoscope housing 1 is as shown in Fig. 1, with the similar slots 4 and 5 for the film pictures. Ground glasses 6, 7 or other diffusing means is mounted between the film and the light source. In this modification, as indeed in the other modifications, the diffusing screens may also be colored suitably to serve as color filters. In this present form of the invention, a magazine 16 is attached in front of the diffusing screen, so as to hold a light source, such as small electric bulbs 17 and 18, before each ground glass. I have found bulbs of flash light type to be suitable. The magazine 16 also contains suitable energizing means, such as small dry cell 19. Contained also in the magazine are means for independently controlling the intensity of each light. Thus, as shown, bulbs 17, 18 may be inserted through metal strips 20, 21, which also serve as parallel conductors between the lamps and the cell 19. The circuit may be completed, and further support afforded for the lamps, by metal strip 22 which extends across the housing 16. The middle portion of strip 22 is bent to afford spring contact with one pole of cell 19.

As shown in Fig. 7, one branch 24 of the parallel connectors comprises a rheostat 23 or other variable resistance so that the intensity of the two lamps may be altered relatively to each other. The effect of varying the intensity of the lamps is to alter the composite color impression in the stereoscopic image from the two viewing lenses. It is within the purview of this invention to introduce color from the lamps if desired, and to use these lamps in conjunction with other modifications of this invention, such as the modifications herein illustrated.

Various alterations will occur within the scope of this invention and the appended claims. For example, these principles may be extended not only to stereoscopic structure for viewing transparent pictures, but also to such as are suitable for viewing pictures by reflected light.

Advantages of this invention will be apparent on consideration that the ultimate composite impression of color in a stereoscopic view is complex, and subject to many variable conditions. For example, in making the original negatives as well as in printing the positives for viewing, the photographic emulsions vary according to the sources, and even according to different batches of emulsion from the same manufacturer. This is particularly true where accurate color rendering is sought. Moreover, color filters used either in photographing negatives or in viewing the positives exhibit variations in the color transmitted. Also, the light and other factors of exposure of the negative introduce differ-

ences between otherwise similar views, when the color is considered. Particularly important is the fact that different human beings who use the stereoscope differ in sensitiveness to given color 5 stimuli, and therefore without means for color control individuals would view a given stereoscopic picture with differing color effects. Even the eyes of a given person differ from time to time as to color response. Also the light for 10 viewing stereoscopic pictures varies, as for example from reflection by one surface or another to the pictures being viewed. The present invention meets these complex and variable conditions in simple manner.

15 According to the provisions of the patent statutes, I have explained the principle and mode of operation of my invention, and have illustrated and described what I now consider to represent its best embodiments. However, I desire to have 20 it understood that, within the scope of the appended claims, the invention may be practiced otherwise than as specifically illustrated and described.

I claim:

25 1. In combination, a pair of stereoscopic pictures in which the separate pictures record different colors of an object, a stereoscope for viewing the pictures, means to illuminate the pictures, means to vary the intensity of illumination of the 30 respective beams from the two pictures and means to impart differences of color to the separate beams from the pictures.

2. In combination, a pair of stereoscopic pictures in which the separate pictures record complementary differences of color of an object, a stereoscope for viewing the pictures, means to illuminate the pictures, means to vary the intensity of light of the separate beams inversely to each other.

sity of illumination of the respective beams from the two pictures progressively and inversely to each other, and means to impart to the separate beams from the pictures complementary differences of color corresponding to the respective 5 pictures.

3. In combination, a pair of stereoscopic pictures in which the separate pictures record complementary differences of color of an object, a stereoscope for viewing the pictures, means to illuminate the pictures, means to vary the intensity of illumination of the respective beams from the two pictures simultaneously and inversely to each other, and means to impart to the separate beams from the pictures complementary differences of color corresponding to the respective 10 pictures.

4. In combination, a pair of stereoscopic pictures in which the separate pictures record complementary differences of color of an object, a stereoscope for viewing the pictures, means to illuminate the pictures, and means to impart to the separate beams from the pictures complementary differences of color corresponding to the respective 15 pictures, said coloring means being adapted to vary the intensity of light of the separate beams inversely to each other.

5. In combination, a pair of stereoscopic pictures in which the separate pictures record different colors of an object, a stereoscope for viewing the pictures, means to illuminate the pictures, means to impart differences of color to the separate beams from the pictures, and means comprising a variable diaphragm to vary the intensity of illumination of the respective beams from 30 the two pictures.

JOHN B. N. CARDOZA.
